(57) **CLAIM**

The ornamental design for an exercise bar as shown and described.

DESCRIPTION

FIG. 1 is a perspective view of an exercise bar according to the claimed design;

FIG. 2 is a rear elevation view thereof;

FIG. 3 is a front elevation view thereof;

FIG. 4 is a right side elevation view thereof, the left side elevation view being a mirror image thereof;

FIG. 5 is a top plan view thereof; and,

FIG. 6 is a bottom plan view thereof.

The broken lines shown in the drawings illustrate portions of the exercise bar that form no part of the claimed design.

1 Claim, 6 Drawing Sheets
